Primary Examiner — Amy C Wierenga*Assistant Examiner* — Grace Doyle(74) Attorney, Agent, or Firm — Polson Intellectual Property Law P.C.; Margaret Polson(57) CLAIM

The ornamental design for a band ornament as shown and described.

DESCRIPTION

FIG. 1 is an isometric view of a band ornament.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines define the bounds of the claimed design and form no part thereof.

1 Claim, 4 Drawing Sheets(56)
